UNITED STATES PATENT OFFICE.

HERMAN ELSAS, OF NEW YORK, N. Y.

STOCK FOR VENDING-MACHINES.

1,116,399.

Specification of Letters Patent. Patented Nov. 10, 1914.

Application filed December 16, 1912. Serial No. 736,995.

To all whom it may concern:

Be it known that I, HERMAN ELSAS, a citizen of the United States, and a resident of New York, in the county of New York and 5 State of New York, have invented certain new and useful Improvements in Stock for Vending-Machines, of which the following is a specification.

This invention relates to stock for vending machines and particularly to that class 10 of such machines as are adapted for vending or dispensing nested paper cups.

The object of my improvements is to provide a stock of the class specified having 15 features of attractiveness and salability in excess of those heretofore provided.

My improvements are illustrated in their preferred embodiment in the drawing accompanying this specification wherein—

20 Figure 1 is a cross sectional elevation showing conventionally the discharge end of a vending or dispensing machine and containing a supply of my improved stock. Fig. 2 is a perspective view of a detail of my 25 improvements.

My improved stock for vending or dispensing machines includes a plurality of nested receptacles herein illustrated as paper drinking cups and each thereof containing 30 a piece or pieces of merchandise; said stock is therefore seen to comprise a plurality of vendible packages each including a receptacle having a piece of merchandise therein.

35 As illustrated the delivery end of said vending machine may comprise tubular portion 2 having a plurality of supports as 3 for engagement with and for supporting the stack of nested cups by engagement with 40 the flange of the lowermost cup in the stack. Said stack is illustrated as including cups or receptacles 4, 5, 6 and 7, cup 8 having been discharged and illustrated as falling

from the receptacle. Preferably I provide pieces or wrapped pluralities of pieces of 45 merchandise, as 9, of such thickness as to separate the receptacles between which said merchandise lies a greater distance than those receptacles would be separated in the absence of said merchandise. This is clearly 50 illustrated by merchandise 9 lying between cups 4 and 5 in contrast with thinner merchandise 13 lying between cups 6 and 7. In the former case the upstanding walls of 55 cups 4 and 5 are separated from one another as shown at 12, while in the case of cups 6 and 7 the corresponding walls are in contact as shown at 14. The object of thus separating said cups is to facilitate the vending thereof by preventing the upstanding walls 60 of one cup sticking to or becoming wedged against those of the adjacent cup.

Another feature of my improvements comprises the peculiar merchandise wrapping illustrated in Fig. 2 wherein cover 10 65 has corners as 11 projecting beyond said merchandise and said corners are turned downwardly whereby feet are provided for spacing the containing cup from the cup nested therein, all clearly shown in Fig. 1. 70

I claim:

The combination of a plurality of nested receptacles with a package of merchandise between two of said receptacles, said package having corners projecting beyond said 75 merchandise and folded against said package, whereby feet are provided for spacing said two receptacles from each other.

Signed at New York, in the county of New York and State of New York, this 13th 80 day of December, 1912, before two subscribing witnesses.

HERMAN ELSAS.
